UNITED STATES PATENT OFFICE.

FERNAND TURRETTINI, OF GENEVA, SWITZERLAND.

INSTRUMENT ADAPTED TO DISCLOSE THE DIFFERENCE ACTUALLY EXISTING
BETWEEN PIECES WHICH SHOULD BE OF THE SAME ACTUAL SIZE.

1,400,331.

Specification of Letters Patent. Patented Dec. 13, 1921.

Application filed February 26, 1921. Serial No. 448,236.

To all whom it may concern:

Be it known that I, FERNAND TURRETTINI, a citizen of Switzerland, residing at Geneva, Canton of Geneva, in the Confederation of Switzerland, have invented certain new and useful improvements in an instrument adapted to disclose the difference actually existing between pieces which should be of the same actual size, of which the following 10 is a specification.

The object of the present invention is an instrument adapted to disclose with an extremely great precision the difference actually existing between pieces which should be 15 of the same actual size.

The instrument can also be used as a contact indicator showing by the displacement of its index needle very accurately the position or the moment in which it enters into 20 contact with any other body.

The instrument comprises an anvil acting upon a rocking lever having two arms of very unequal length, the short arm being connected to the anvil and the long one carrying 25 an index or forming itself an index, marking on a scale the position of the lever. The anvil works upon the lever by means of a knife edge. The rotating axis of the lever is represented by another knife edge. This 30 arrangement is adapted to reduce the friction caused by the rocking of the lever to a minimum.

In order to make sure that this friction becomes a real minimum another additional 35 condition requires consideration, namely: when the rocking system is in its mean position the edges of both knives should be in the same plane perpendicular to the axis of the anvil.

40 In the drawing Figure 1, is a central longitudinal cross section of part of the apparatus forming my present invention.

Fig. 2, is a cross section of the same parts taken at right angles to the position as illustrated in Fig. 1.

Fig. 3, is an elevation and partial cross section of another part of the apparatus.

Fig. 4, is a plan view of the parts of the apparatus shown in Fig. 3.

50 Fig. 5, is an elevation and partial cross section of the same parts as shown in Fig. 3, taken at the position 90 degrees from those shown in Fig. 3.

Fig. 6, is an elevation and partial cross

section of apparatus with the parts assembled and 55

Fig. 7, is a similar view showing the indicator of the apparatus in a different position.

In Figs. 1 and 2 which represent only a portion of the instrument *a* is the anvil of which the extremity *b* constitutes the measuring face. A fork shaped member *c* is fixed upon the anvil. The prongs *d* and *e* of said fork *c* are connected by a knife whose edge *f*, interrupted in its middle portion, constitutes one of the pivoting points of the rocking system. Since the fork *c* carrying the edge *f* is rigidly fixed upon the anvil *a*, said edge *f* will be subjected to all the movements 60 which the face *b* of anvil *a* will make. A spring *g* tends constantly to push the anvil out of the body *h* of the instrument. Another knife *r* is carried by a member *s* which latter is adapted to slide in a plane perpendicular to the axis of the anvil. The two screws *t*¹ and *t*² advancing in opposite directions are provided for displacing said member *s* laterally and to thereby regulate the distance *u* between the knife edges *r* and 70 *f* in a plane perpendicular to the axis of the anvil. 75

According to Figs. 2, 3, 4 and 5, the rocking member comprises a plate *i*, having a central hole *j* and in suitable ledges a triangular groove *k*¹, the apex of which is exactly in the plane of the face *m* of plate *i*. A second plate *n* of very hard metal is tightly secured upon the face *m* of plate *i*. Therefore the bottom face *o* of plate *n*, which 85 face is in close contact with the top face *m* of plate *i*, is also in the plane passing through the apex of the triangular groove *k*—*l*. Upon the plate *i* the index needle *p* and a spring *q* is fixed which tends to lift the 90 plate *i*. 95

If the rocking portion is put on the bottom part of the instrument in such a manner that the knife edge *f* bears into the groove *k*—*l* of plate *i* (Fig. 6) and that the edge of 100 knife *r* bears on the face *o* of plate *n*, a small lateral distance *u* being provided for between said two edges, *f*, *r*, in the direction opposite the side to which the spring *q* is fixed, then the whole rocking system which is under 105 the action of the springs *q* and *g* but is retained by the knives *f* and *r* will usually be in perfect equilibrium.

The angle between the index needle p and a plane perpendicular to the axis of the anvil a depends upon the distance w (Fig. 7) in the direction parallel to the axis of the anvil a . If the anvil is moved, the distance w will be altered and the index needle will assume a new steadied position of equilibrium.

The angular range of motion of the index needle p , being small and symmetric to its mean position, in which the bottom face o of plate n is perpendicular to the axis of the anvil a the displacements of the index needle p will be very closely proportional to those of the anvil.

It will be observed that an excessive displacement of the anvil cannot cause a damage to the instrument, although the angular range of the rocking system is rather small. If the distance w becomes excessively great (Fig. 7) the spring q only acts upon the rocking system, which is not subjected to any other prejudicial strains. When the distance w does exceed a given limit, the face o of plate n will simply cease to bear upon the edge of knife r .

The multiplying capacity of the instrument depends upon the ratio of the length of the index needle p to the adjustable distance u (Figs. 1 and 2). Therefore the multiplying capacity of the instrument according to invention may be chosen at will.

The whole instrument, except the projecting end of the anvil a , may be inclosed in a protective tubular case, a suitably arranged glass plate making it possible to read the indications of the scale (Figs. 6 and 7.)

I claim as my invention:

1. In a needle indicator and in combination a body member, a measuring anvil adapted to slide within said body member, a spring for acting upon said anvil, a knife rigidly connected to said anvil, a rocking lever having two arms of unequal length, the longer one being adapted for serving as an index, a second knife, means for adjusting said second knife, a plate having a groove adapted for receiving the edge of the knife rigidly connected to the anvil, a second plate tightly fixed upon said first plate, the apex of the groove in said first plate being in the plane passing through the bottom surface of said second plate and through the edge of said adjustable knife, substantially as described.

2. In a needle indicator and in combination a body member, a measuring anvil

adapted to slide within said body member, a spring for acting upon said anvil, a knife rigidly connected to said anvil, a rocking lever having two arms of unequal length, the longer one being adapted for serving as an index, a second knife, means for adjusting said second knife, a plate having a groove being adapted to receive the edge of the knife rigidly connected to the anvil, a second plate fixed upon said first plate, the apex of the groove in said first plate being in the plane passing through the bottom surface of said second plate and through the edge of said adjustable knife, the edges of both knives being directed one against the other, said edges being adapted to be separated from one another when the anvil touches any piece to be measured, the rocking device being adapted to remain in contact with the knife edges by means of a spring, to avoid damaging the instrument in the event of an excessive or abrupt displacement of the measuring anvil, substantially as described.

3. In a needle indicator in combination a body member, a measuring anvil adapted to slide within said body member, a spring for acting upon said anvil, a knife rigidly connected to said anvil, a rocking lever having two arms of unequal length, the longer one being adapted for serving as an index, a second knife, means for adjusting said second knife, a plate having a groove adapted to receive the edge of the knife rigidly connected to the anvil, a second plate fixed upon said first plate, the apex of the groove in said first plate being in the plane passing through the bottom surface of said second plate and through the edge of said adjustable knife, the edges of both knives being directed one against the other, said edges being adapted to be separated from one another when the anvil touches any piece to be measured, the rocking device being adapted to remain in contact with the knife edges by means of a spring to avoid damaging the instrument in the event of an excessive or abrupt displacement of the measuring anvil, and a tubular case containing said needle indicator, and having a transparent portion covering a scale, substantially as described.

In testimony whereof I have affixed my signature in presence of two witnesses.

FERNAND TURRETTINI.
